UNITED STATES PATENT OFFICE.

EDWARD SCHWARTZ, OF CHICAGO, ILLINOIS, ASSIGNOR, BY MESNE ASSIGNMENTS, TO PELOUZE MANUFACTURING COMPANY, OF CHICAGO, ILLINOIS, A CORPORATION OF ILLINOIS.

ELECTRICALLY-HEATED COMB.

1,033,122.

Specification of Letters Patent. Patented July 23, 1912.

Application filed January 2, 1912. Serial No. 668,933.

To all whom it may concern:

Be it known that I, EDWARD SCHWARTZ, a citizen of the United States of America, and a resident of Chicago, county of Cook, 5 State of Illinois, have invented certain new and useful Improvements in Electrically-Heated Combs, of which the following is a specification.

The main objects of this invention are to 10 provide an improved form of electrically heated curling iron and comb wherein the curling iron shield and comb are each adapted to be detachably secured to the electric heater and rigidly held in position thereon; 15 to provide an improved construction of the electric heater and housing therefor; and to provide an improved form of electrical connection between the heating element and the conductors leading to the source of electricity. 20

An illustrative embodiment of this invention is shown in the accompanying drawings, in which:—

Figure 1 is a perspective view of a device 25 constructed according to this invention and having the curling iron shield in position thereon. Fig. 2 is a longitudinal sectional elevation of the device adapted to serve as a comb. Fig. 3 is a rear end view of the 30 comb removed from the heater. Fig. 4 is a front end view of the heater with the comb removed. Fig. 5 is a fragmentary detail illustrating the position of the notch in the comb-back. Fig. 6 is an enlarged sectional 35 detail of the curling iron shield and the part of the heater adjacent to which it is attached.

In the construction shown in the drawings, the comb 1 is formed from a piece of 40 sheet metal or a casting, and has a plurality of teeth 2 cut or formed therein of the usual shape, and the back 3 is provided with a longitudinal bore 4.

The comb 1 is adapted to be placed on an 45 electric heater, preferably a cylindrical rod adapted to serve as a hair curler and comprising a casing 5 in which an electric heating element 6 is housed, such heating element being constructed in the form of a rod 50 or tube 7 of insulating material, placed upon a metal reinforcing tube 8 and upon which is wound the resistance wire 9. The heating element is free to rotate as a unit relatively to the casing upon the rings 10. The casing 5 is provided with a handle 11, of

wood or other heat insulating material, and has extending forwardly therefrom a flange 12, concentric with the casing 5, and spaced away therefrom to form an annular recess 13, into which the end 14 of the comb back 3 is received. A shoulder 15 is formed on the casing 5 within the recess 13, which is adapted to be received into a notch 16 in the end 14 of the comb back 3, when the comb is placed upon the casing 5. The shoulder 15 and notch 16 secure the comb and heater against relative rotation.

When the comb is removed, the heater may be used in the usual manner as a curling iron. A shield 17 is usually used with 70 the heater when curling is done. The shield 17 fits over the tube 5 and is secured to the heater by a clip or saddle 18, to which it is pivoted at 19. The saddle 18 is designed to be retained in the recess 13 and secured 75 against displacement by the spring 20, which embraces the pivot 19, and has one part bearing against the under side of the rear end of the shield 17 (Fig. 6), and the other part seated in the groove 21 on the 80 flange 12. The shield 17 is provided with a thumb button 22 for operating the shield.

Electrical conductors 23 in the form of a cord are provided with the usual socket plug 24 and are secured to the end of the handle 85 11 for connecting the heating element 6 with a source of electricity. The electrical connection between the heating element 6 and the conductors 23 is completed within the handle 11. This connection comprises a 90 pair of sockets or tubular contacts 25 carried by a block of insulating material 26 rigid on the rod 27 extending rearwardly from the heating element 6, and resilient rods 28 carried in the block 29 of insulating 95 material, to which the conductors 23 are secured. The rod 27 is rigidly secured to the tube 8 by a ring 8A which has a driving fit with the respective parts and constitutes an 100 electrical connection between them. One of the contact tubes 25 is connected to one end of the resistance wire 9, said wire being wound upon the insulation 30 covering the rod 27 and having its other end connected to the tube 8 at its forward end. The other tube 25 is electrically connected to the rod 105 27 by a U-shaped member 31 secured in the block 26 to bear against said tube and rod. The rods 28 are respectively connected to the conductors 23, being clamped at their 110

ends over the ends of said conductors and retained in a disk 33 adapted to be received in the end of the block 29. A second disk 34 is placed inward of the disk 33, which holds 5 the conductors 23 and rods 28 apart. The rods 28 are normally sprung apart or bent so that when they are inserted into the tubes, a firm contact between the rods and the tubes is obtained. The outer block 29 has rotary 10 connection with a sleeve 35 and is threaded into the handle to secure the heating element against being accidentally withdrawn.

To operate the device, the socket plug 24 is screwed into a lamp socket in the usual 15 manner. The connection between the heating element and the conductors 23 need not be disturbed for this purpose, as the rotation of the heating element will remove the twist from the cord. The double prong and 20 socket connection between the cord and heating element enables them to be readily connected or disconnected and is not disturbed in any way by a torsional strain on the cord as the plug is screwed into the line socket. 25 The comb 1 or shield 17 is placed upon or removed from the casing 5 according as the device is to be used as a drier or curler. The tubular comb back forms an efficient means for transferring heat from the heater 30 to the prongs. The shield 17 is quickly and conveniently placed upon the heater 5 by slipping the saddle 18 under the flange 12 and the spring 20 into the groove 21.

Although but one specific embodiment of 35 this invention is herein shown and described, it will be understood that some of the details of the construction shown may be altered or omitted without departing from the spirit of this invention, as defined by 40 the following claims.

I claim:

1. In a device of the class described, the combination of a casing, a handle attached thereto, a heating element housed in said 45 casing, a comb having a bore formed in the back thereof adapted to receive said casing, and a coacting notch and shoulder on said casing and comb back for securing them against relative rotation.
- 50 2. In a device of the class described, the combination of a casing, a handle attached thereto, a heating element housed in said casing, a comb having a bore formed in the back thereof adapted to receive said casing, and a shoulder on said casing, and said 55 comb back having a notch therein adapted to receive said shoulder for securing said comb and casing against relative movement.
3. In a device of the class described, the 60 combination of a casing, a heating element housed in said casing, a handle attached thereto and having a flange arranged con-

centrically with respect to said casing so as to provide an annular recess between said casing and flange, a comb having a bore 65 formed in the back thereof adapted to receive said casing and having the end of said back shaped to fit in said recess, and a shoulder located in said recess, said back having a notch therein adapted to receive 70 said shoulder for securing said comb and casing against relative rotation.

4. In a device of the class described, the combination of a comb, a handle attached thereto, a heating element housed in the 75 back of said comb, conductors leading to a source of electricity, blocks of insulating material housed in said handle and respectively secured to said heating element and to said conductors, an electrical connection between said blocks, comprising 80 tubes on one of said blocks and resilient rods on the other block, said rods normally occupying an unaligned position with respect to said tubes when separated therefrom.

5. In a device of the class described, the combination of a heater having a handle in alinement therewith, a rotary heating element in said heater, a conductor cord, 90 means connecting said cord and heater and comprising a pair of contact blocks respectively connected to the cord and heater and having interfitting prong and socket contact members, the one of said blocks which 95 is nearest the cord being swiveled in said handle.

6. In a device of the class described, the combination of a heater having a handle in alinement therewith, a rotary heating 100 element in said heater, a conductor cord, means connecting said cord and heater and comprising a pair of contact blocks respectively connected to the cord and heater and having interfitting prong and socket contact members, and a sleeve having swiveled 105 connection with the contact block of said cord and threaded into said handle.

7. In a device of the class described, the combination of a heater having a handle 110 in alinement therewith and having an annular recess formed at the juncture of said heater and handle, and an attachment for said device comprising a part adapted to be secured in said annular recess for securing 115 said heater and attachment against displacement.

Signed at Chicago this 28 day of December 1911.

EDWARD SCHWARTZ.
